United States Patent Office

Des. 213,369
Patented Feb. 25, 1969

213,369

COMBINED LAVATORY AND CABINET

Nicholas Peter Arvan, Berwyn, Ill., assignor to Crane Co.,
Chicago, Ill., a corporation of Illinois

Filed Feb. 28, 1968, Ser. No. 10,759

Term of patent 14 years

U.S. Cl. D23—59
Int. Cl. D23—02

The broken line representation of a base in FIGURE 1 is for purposes of illustration only.

I claim:

The ornamental design for a combined lavatory and cabinet, as shown and described.
